UNITED STATES PATENT OFFICE.

GEORGE BECK, OF DENVER, COLORADO.

AUTOMATIC TRAIN-STOP.

1,316,759.

Specification of Letters Patent. Patented Sept. 23, 1919.

Application filed August 19, 1918. Serial No. 250,592.

To all whom it may concern:

Be it known that I, GEORGE BECK, a citizen of the United States, residing at the city and county of Denver and State of Colorado, have invented certain new and useful Improvements in Automatic Train-Stops; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to train stops and the object is the provision of such a device which will automatically cut off the steam and apply the air in several applications if the engine runs past a signal.

20 Briefly, the invention comprises two rotary cams operated by a motor, one cam controlling a reciprocating rod cutting off the steam in one revolution while the other cam controls a reciprocating rod which ap-

25 plies the air in three revolutions, thus making three applications of air instead of only one sudden application. This mechanism is mounted on the engine. A trip adapted to operate the trip arm is mounted on each

30 semaphore along the track and when the semaphore arm is raised the trip is projected into the path of the trip arm carried by the engine. If the engine passes the signal the motor is started and operates the

35 cams cutting off the steam and stopping the train with successive easy applications of air. In the drawings:

Figure 1 is a vertical section on the line 1—1 of Fig. 2.

40 Fig. 2 is a horizontal section on the line 2—2 of Fig. 1.

Fig. 3 is a fragmentary view from the line 3—3 of Fig. 1.

Fig. 4 indicates the mounting of the de-

45 vice on an engine.

Fig. 5 is a plan view of the reciprocating throttle and air controlling rods from line 5—5 of Fig. 4.

Fig. 6 is a fragmentary view from line

50 6—6 of Fig. 5.

Fig. 7 is a plan indicating the relation of the parts on the engine and the projecting trip of the semaphore.

Fig. 8 is an enlarged section on line 8 of

55 Fig. 5.

Fig. 9 shows the remote face of the rear cam of Fig. 1.

Fig. 10 is a fragmentary elevation showing the relation of the trip arm on the engine and the trip of the semaphore. 60

A casing 12, mounted upon the running board A of the engine and having a hinged cover 13 retained by a lock 14, contains the operating mechanism for the throttle control rod 15 and the air control rod 16 which protrude therefrom. The rod 15 is operated by a cam 17 and the rod 16 by a cam 18, these cams being mounted upon opposite faces of a gear wheel 19 and having cam grooves 20 and 21 respectively. The gear wheel 19 is 70 mounted upon a shaft 22 supported in the walls of the casing. The gear 19 is driven by a worm 25 on shaft 26 extending from an air motor 27 whose exhaust is conducted to a whistle 127. 75

Air is admitted to the motor through pipe 28 which is an extension of air pipe 29, the passage of air being controlled by a valve 30. The valve stem 31 extends to opposite sides of the engine and has on both ends trip arms 32. A disk 33 is also mounted on the valve stem 31 being provided with shoulders 35, with one of which the offset end 36 of lever 37 will engage when a trip arm 32 is moved in either direction. The end 36 is urged 85 into engagement with disk 33 by spring 38 connected with the lever 37.

A trip 40 having a roller 41 thereon for engagement with trip arm 32 is mounted in a protecting casing 42 mounted on each 90 semaphore B along the track. This trip rod is projected through the medium of a pitman 43 mounted on a gear 44 suitably connected for operation by the usual mechanism of the semaphore. 95

The arms 15 and 16 within the casing 12 are slotted at 50 to run on a guide rod 51 mounted in the walls of the casing. The inner end of rod 15 is provided with a pin 115 (Fig. 1) projecting into cam groove 20, 100 and the inner end of rod 16 has a pin 116 (Fig. 9) projecting into cam groove 21, the rods being reciprocated through the medium of these pins. Springs 60 positioned between the casing walls and the gear wheel 19 hold the rods 15 and 16 in operative position against the cams 17 and 18. 105

Outside the casing the rods 15 and 16 are provided with universal joints 52, the 110

rods extending beyond these joints into the cab where they engage throttle and air controls. Rod 15 is provided with a slot 53 which engages a laterally extending arm 54 on throttle lever 55. The rod 16 is provided with a rack 56 engaging a pinion 57 on the air control.

The rod 16 has a depending arm 216 adapted to engage the upper end 137 of lever 37 to release the offset 36 from shoulder 35 to cut off the air when rod 16 has reached its foremost position after having made the last application of air.

A register 100 is operated by arms 215 on rod 15.

In operation, assuming that the engine passes a signal, the end of the rod 40 carrying the roller 41 will have been projected into the path of the trip arm 32 by the 20 semaphore, whereby the arm 32 will be tripped opening the valve 30 and causing rotation of the disk 33 until one of the shoulders 35 passes the offset 36 and allows it to spring into engagement therewith 25 which holds the valve open. The gear wheel 19 will then be rotated through the medium of the air motor 27 and worm 25. The cam groove 20 has but one convolution which causes a complete movement of rod 15 on 30 one revolution and cuts off the steam. The cam groove 21 has three convolutions so that the air will be applied in three applications. When the third application is made the depending arm 216 in making the last step of 35 its forward movement engages the upper end 137 of the lever 37 and releases offset 36 from shoulder 35 permitting spring 34 to restore disk 33 to normal position, thus cutting off the air.

40 The air and throttle controls operated by the rods 15 and 16 will preferably be separate from the usual controls so that the mechanism of this invention will not in any way interfere with the ordinary operation 45 of the usual controls.

When an engine has thus passed a signal, it becomes necessary for the engineer to open the cover 13 of the casing 12 in order to reset the mechanism and release his throttle 50 before the engine can again move under its own steam. The resetting is accomplished by manually shifting the rods 15 and 16 laterally against the tension of springs 60 to release them from the cams, moving them 55 longitudinally and replacing the pins 115 and 116 in their respective cam grooves. The slot 53 in rod 15 is sufficiently long to permit restoring of the rod to its original position without moving the throttle lever 60 55. Upon returning to the cab the engineer will then manually shift the lever 55 before he can use the steam through the ordinary throttle lever.

65 By extending the valve rod 31 out on both sides of the engine and providing two shoul-

ders 35, one of which engages offset 36 upon movement of the valve rod in either direction, the device is made operable whether the engine is moving forward or backward.

Movement of the rod 15 to shut off the 70 steam will cause the fingers 215 thereon to operate the arm 101 of the register 100. By this means officials may always determine whether an engineer has run by his signal.

It will be seen from the foregoing that 75 a comparatively simple device is provided adapted to be set in operation by simple mechanism controlled by the usual semaphore along the track, which will automatically cut off the steam and apply the air in 80 a plurality of successive applications in much the same way that the air is normally manually applied. The timing may be determined by the gearing and the speed of the motor.

85 It will be noted that by leading the exhaust from the air motor to the whistle 127 that an audible signal will be made immediately upon the starting of the motor.

I claim:

1. In a train stop, a throttle control and an air control, a rotary member having cam grooves on opposite faces, a reciprocating arm operable by and engaging in one groove to operate the air control, and a second reciprocating arm engaging in the other groove to operate the throttle control. 90

2. In an automatic train stop, air applying means, means to operate said applying means to apply air in a plurality of successive applications, a reciprocating arm operated by said operating means and connected to said applying means, and means adapted to be controlled by a signal for controlling said operating means. 100

3. In an automatic train stop, a throttle control and an air control, a rotary cam member operating said throttle control to cut off steam and operating said air control to apply the air in a plurality of successive 110 applications, and means operable by a signal to operate said control-operating means.

4. In an automatic stop, a steam control and an air control, cam means operating said steam control to cut off the steam, and 115 cam means operating said air control to apply the air gradually, and signal-operated means to operate said control-operating means.

5. In an automatic stop, the combination 120 with a semaphore operated trip, of a steam control, an air control, rotary cam means to operate said steam control to cut off the steam, and rotary cam means to operate said air control to apply the air gradually, said 125 control-operating means being actuated by said trip.

6. In an automatic stop, the combination 130 with a semaphore operated trip, of a steam control, an air control, a cam member to

- operate said controls to cut off the steam and to apply said air in a plurality of successive applications, said control-operating means including a trip arm operable by said trip.
- 5 7. In an automatic stop, the combination with a semaphore-operated trip, of an air control, and a member having a cam groove to operate said control to apply the air gradually, said control-operating means including a member operable by said trip.
- 10 8. In an automatic stop, an air control, means to operate said control to apply the air gradually, means operable by a signal to operate said control-operating means, and
- 15 15 means to automatically cut off the air when the air-application is complete.
9. In an automatic train stop, an air control, a cam member, a connection between said control and said cam member, said
- 20 member having a cam groove therein adapted to operate said connection gradually to apply the air gradually, and means to move said cam member adapted to be controlled by a signal-operated means.
- 25 10. In an automatic train stop, an air control, a cam member, a connection between said control and said cam member, said member having a cam groove therein adapted to operate said connection in successive
- 30 stages to apply the air in a plurality of successive applications, signal-controlled means adapted to actuate said cam member, and means to automatically cut off the air when the air-application is complete.
- 35 11. In an automatic train stop, a cam member, an air control, a throttle control, cam grooves on opposite faces of said cam member, connections between said controls and said cam grooves, said grooves being
- 40 adapted to cut off the steam and apply the air respectively through said connections, the cam groove controlling the air supply being adapted to apply the air in a plurality of successive applications, and signal-con-
- 45 trolled means adapted to actuate said cam member.
12. In a train stop, a throttle control and

an air control, a rotary member having cam grooves on opposite faces, a reciprocating arm operable by and engaging in one groove 50 to operate the air control, and a second reciprocating arm engaging in the other groove to operate the throttle control, the air control groove having a plurality of sections in order to apply the air in a plurality 55 of successive applications.

13. In a train stop, a throttle control and an air control, a rotary member having cam grooves on opposite faces, a reciprocating arm operable by and engaging in one groove 60 to operate the air control, and a second reciprocating arm engaging in the other groove to operate the throttle control, the throttle control arm having an elongated slot to receive loosely a throttle operating 65 member.

14. In a train stop, air applying means, means to operate said applying means, a fluid motor to drive said operating means, a fluid supply conduit for said motor, a 70 spring-controlled valve in said conduit, a trip arm connected with said valve, and a semaphore-operated trip to engage said arm, the spring on said valve being adapted to restore said valve to cut off the fluid to the 75 motor.

15. In a train stop, air applying means, means to operate said applying means, a connection between said applying means and said operating means, comprising a reciprocating arm having a projection, a fluid motor to drive said operating means, a fluid supply conduit for said motor, a spring-controlled valve in said conduit, a trip arm connected with said valve and a spring operated 80 lever to lock said valve in open position, said projection on said reciprocating arm being adapted near one limit of its reciprocation to move said lever to release said spring-controlled valve for cutting off fluid to said 85 motor.

In testimony whereof I affix my signature.

GEORGE BECK.
